CAM CONTROLLED WORK HOLDER

Carl A. Ulfves, Worcester, Mass.

Application September 18, 1950, Serial No. 185,442

7 Claims. (Cl. 51—232)

1

This invention relates to a cam controlled work holder and the principal object of the invention resides in the provision of a device employing a plurality of adjustable cams for moving engagement with a fixed fence or the like and including a base and work holder thereon whereby the device may be moved with the cams in contact with the fence imparting to the device a particular predetermined path of travel so that a work piece thereon may be accurately cut or ground depending on the formation and relative adjustment of the cams.

Other objects and advantages of the invention will appear hereinafter.

Reference is to be had to the accompanying drawings in which

Fig. 1 is a top plan view of the device;

Fig. 2 is a view in side elevation thereof;

Fig. 3 is a section on line 3—3 of Fig. 1;

Fig. 4 is an end view;

Figs. 5 and 6 illustrate the device in use;

Fig. 7 is a sectional view illustrating the use of an attachment; and

Fig. 8 is a bottom plan view of a base plug.

A base 10 may be provided for supporting the device under consideration as on the bed of a grinder or the like, and this base has slidably mounted thereon a pair of semi-circular cam elements 12 and 14 each of which is provided with an accurately ground flat diametrical face indicated at 16, each said face having centrally thereof a semi-circular depression as 18 for the reception of a removable base held plug or the like 20, the latter having in its top surface a ball bearing indicated at 22 for a purpose to be described.

A top plate 24 is provided with upwardly extending rectilinear side flanges 26 to which are detachably secured clamping plates 28 for the purpose of clamping a V-block 30 by means of slots 32 therein as best shown in Fig. 4. The V-block is adapted to form a clamp for the work W so as to center the same as desired but particularly in aligned axial relation with the plug 20.

The two cams 12 and 14 are adjustably located and secured to plate 24 by means of fasteners such as screws 34 passing through slots 36 in the cams and threaded into the top plate 24, see Fig. 3. Thus the two semi-circular cams may be adjustable where desired to and from each other. They may be placed together forming a circle as in Fig. 1, or they may be separated to any degree desired, see Fig. 5, forming in essence an oval. They may be even turned back-

2

to-back to form essentially a rectangle, see Fig. 6.

A yoke or similar device 38 may be used to clamp the work to the V-block and a set screw 40 may be employed in said yoke to secure the work tightly thereby and to enable the clamping of smaller size work pieces. Of course, the V-block may be adjustably moved along plates 28 and may be clamped thereby in any desired position along the top plate 24.

10 The base plate 10 is provided with a guide rail or fence 42 which may be secured thereto in any desired way as by screws 44. This fence is preferably provided with a lip or flange 46 taking into circular grooves 48 in the cams and it will be observed that this construction provides that the cams may be moved along or with respect to the fence, but will not tend to become separated therefrom due to the overhanging flange 46. The V-block has an undercut 47 to 20 accommodate flange 49 on the work W.

Referring now to Fig. 5 and assuming that the work is clamped as described, the top plate 24 is moved as for instance by hand so that the cam surfaces engage the fence 42 and if the 25 cams are spaced as shown in Fig. 5 the path of movement of plate 24 can be only that of an oval and the larger axis thereof is determined by the degree of separation of the cams. Therefore, the work will be moved in a path relative to a fixed tool such as a grinding wheel so 30 as to grind a smaller oval thereon.

The plug 20 defines the limits of movement of the device as long as it is in place, but it may be removed if desired. It will be observed that 35 the ball bearing 22 projects slightly above the bottom surface of plate 24 and into a longitudinal slot 50 in the bottom of plate 24 again guiding the top plate even though the cams may not be in engagement with the plug. In other 40 words, the device may be moved on the plate 10 but only as controlled by the plug and the cam surfaces against the fence 42.

As shown in Fig. 6, the cams may be reversed and, therefore, a rectangular shape may be 45 ground or cut on the work piece.

Fig. 7 illustrates a condition employing a removable plug 52 which may take up the entire hole 53 in the plate 24 but which has a portion having a half surface or part having an exactly 50 ground diametrical edge 54. Johansson blocks may be used to correctly position, for instance, cam 12 from the surface 54, whereupon the plug is turned around 180° from the Fig. 1 position and cam 14 may then be accurately adjusted 55 from said surface 54.

This plug is insertable and removable from top or bottom of plate 24, and fits snugly enough so that it will not fall through the plate.

It will be seen that this device may be used to accurately form or grind tools, particularly punches, and all shapes from a circle to an oval having a relatively long major axis, are easily ground as well as rectangular shapes as illustrated in Fig. 6.

Having thus described my invention and the advantages thereof, I do not wish to be limited to the details herein disclosed otherwise than as set forth in the claims, but what I claim is:

1. A device of the class described comprising a plate, a work holder on the plate, a plurality of cams, means to adjustably secure the cams to the plate, each cam having an arc-shaped edge surface and the cams together defining an oval or the like shape to be reproduced on the work, and relatively stationary means to be engaged by the cams remote from the arc-shaped edges thereof to impart a predetermined path of travel to the plate and the work as the plate is rotated relatively to a tool, and means constraining the plate to the predetermined path.

2. A device of the class described comprising a plate, a work holder on the plate, a plurality of cams, means to adjustably secure the cams to the plate, each cam having a curved surface and the cams together defining a shape to be reproduced on the work, and relatively stationary means to be engaged by the cams to impart a predetermined path of travel to the plate and the work as the plate is rotated relatively to a tool, and means constraining the plate to the predetermined path, said last named means comprising a fixed plug working in a slot in the plate and located between the cams so that the plate and work may be traveled only according to the slot and between the cams.

3. A device of the class described comprising a plate, a pair of substantially semi-circular cams adjustably secured thereto, a work holder on the plate, a fence for engagement with the cams as the plate is moved in a rotational manner, and means engaging the plate to provide for moving the same in a restricted path, said cams being engageable with said means to limit the travel of the plate in two directions, a slot in the plate receiving the said means, the slot extending between the cams, so that the slot, means, and cams completely define the path of the plate as it is rotated.

4. A device of the class described comprising a plate, a work holder on the plate, a plurality of cams, means to adjustably secure the cams to the plate, each cam having a curved surface and the cams together defining a shape to be reproduced on the work, and relatively stationary means to be engaged by the cams to impart a predetermined path of travel to the plate and

the work as the plate is rotated relatively to a tool, said plate having a central hole, a plug in the form of a cylinder in the hole and removable therefrom, said plug having a portion thereof in the form of a semi-cylindrical body having a diametrical, axial surface, said plug forming a zero point by the diametrical surface thereof by which to exactly measure the adjustment of the cams from a center point at the center of the hole.

5. A device of the class described comprising a plate, a work holder on the plate, a plurality of substantially semi-circular cams, means to adjustably secure the cams to the plate, said cams having the straight edges facing each other and the cams together defining an oval shape to be reproduced on the work, and relatively stationary means to be engaged by the cams to impart a predetermined path of travel to the plate and the work as the plate is rotated relatively to a tool, said cams being semi-circular and located beneath the plate, said means including a fence for engagement of the cams.

6. A device of the class described comprising a base, a fence thereon, a pair of semi-circular cams resting on the base for engagement with the fence, a top plate above the cams, means to adjustably secure the cams to the top plate, and a work holder on the top plate, a plug in the base rising therefrom between the cams, means on the top plate engaging the plug and positively limiting the extent of travel of the top plate thereby, each cam having a semi-circular recess to receive the plug when the cams are adjusted to form substantially a circle with the diametrical surfaces of the cams substantially contacting each other.

7. A device of the class described comprising a base, a fence thereon, a pair of semi-circular cams resting on the base for engagement with the fence, a top plate above the cams, means to adjustably secure the cams to the top plate, a work holder on the top plate, and a removable central plug having a ground flat surface in an axial plane with respect thereto for measuring the distance of the cams from a center.
